CLAIM

The ornamental design for an accessory mount, as shown and described.

DESCRIPTION

FIG. 1 is left rear isometric view of an accessory mount according to my new design;

FIG. 2 is a right rear isometric view of the accessory mount shown in FIG. 1; and,

FIG. 3 is a rear view of the accessory mount shown in FIG. 1.

(Continued)

The broken lines show portions of the accessory mount that form no part of the claimed design.

1 Claim, 3 Drawing Sheets
